Primary Examiner—James Gandy*Assistant Examiner*—Cathron B. Matta*Attorney, Agent, or Firm*—Jack L. Oney, Jr.; William Scott Andes[57] **CLAIM**

The ornamental design for a dispensing spout, as shown and described.

DESCRIPTION

FIG. 1 is a top view of a dispensing spout, embodying my new design;

FIG. 2 is a back elevational view thereof;

FIG. 3 is a side elevational view thereof, the opposite side elevational view being a mirror image thereof; and,

FIG. 4 is a front elevational view thereof.

The bottom and interior of the spout form no part of the claimed design.
